UNITED STATES PATENT OFFICE.

GEORGE H. HARVEY, OF MIDDLETOWN, OHIO, ASSIGNOR TO THE ENTERPRISE MACHINE COMPANY, OF MIDDLETOWN, OHIO, A CORPORATION OF OHIO.

ROLL PLUG.

Application filed March 10, 1924. Serial No. 697,980.

My invention relates to plugs for insertion into rolls of paper or like substances, to fill the core left in the roll by the drum or shaft upon which it is wound.

5 There are a number of different devices provided in connection with rolls of paper for closing the ends of the roll, and protecting the paper from caving in at the ends because of an open core. Either a wooden 10 plug of some character is inserted, or else the steel tube, or wood core upon which the paper is wound, is permitted to remain within the roll. Both are unsatisfactory.

In handling large rolls of paper at point 15 of delivery, and in moving them about in the paper mill, it is convenient to carry them by means of a crane. The usual mode of engaging the rolls with a crane is to provide for a tong which is inserted with its ends 20 in the ends of the roll. It is my object to provide a core plug for paper rolls which will be strong enough to receive the engaging devices of a crane, and which is well adapted for this purpose.

25 It is further my object to make the core as inexpensive as possible and at the same time to make it effective to the highest degree.

These objects I accomplish by that certain 30 construction and arrangement of parts to be hereinafter more specifically pointed out and claimed.

In the drawings:

Figure 1 is a perspective view of a partial 35 roll of paper with my novel core inserted therein.

Figure 2 is a horizontal section through a roll of paper with the core in place, also illustrating the engaging device of a crane.

This section is taken on the line 2, 2, of 40 Figure 1.

The core is formed of a piece of sheet metal formed with a peripheral flange 1, to be inserted into the open end or core of the paper roll. It has a body 2 corrugated in 45 concentric circles, as indicated, and has a central hole 3, with a flange 4 formed to extend inwardly about the hole.

The roll of paper, or other substance, is shown at 5, and it will be noted that the 50 core is fitted into the end of the roll so that the body will lie flush with the end, and that a rod or finger 6 of a crane can be inserted into the central hole.

The circumferential corrugating of the 55 pieces gives them great strength, and enables them to resist bending when the weight of the roll is supported at the two ends by a crane tong engaging in the holes therein. Furthermore, if it is desired to 60 withdraw the plugs, the central hole permits of ready engagement therewith, while in normal position the plugs are flush with the ends of the paper roll.

Having thus described my invention, what 65 I claim as new and desire to secure by Letters Patent, is:—

A core for paper rolls comprising an integral metallic plate cut and bent forming 70 a circular body corrugated in concentric circles having a peripheral cylindrical flange for insertion into the hole in the end of a paper roll, and having a concentric cylindrical flange of less length than the first mentioned flange for the reception of carrying members. 75

GEORGE H. HARVEY.
